FOREIGN PATENT DOCUMENTS

WO 2023/230273 A1 11/2023

Primary Examiner — Ramzi Almatrahi(74) *Attorney, Agent, or Firm* — McCarter & English, LLP(57) **CLAIM**

The ornamental design for a camera, as shown and described.

DESCRIPTION

FIG. 1 is a top, front, and left side perspective view of a camera showing our new design in a first position;

FIG. 2 is a bottom, rear, and left side perspective view thereof;

FIG. 3 is a left side elevation view thereof;

FIG. 4 is a right side elevation view thereof;

FIG. 5 is front elevation view thereof;

FIG. 6 is a top plan view thereof;

FIG. 7 is a bottom plan view thereof;

FIG. 8 is a top, front, and left side perspective view thereof, shown with the camera in a second position;

FIG. 9 is a bottom, rear, and left side perspective view thereof;

FIG. 10 is a left side elevation view thereof;

FIG. 11 is a right side elevation view thereof;

FIG. 12 is front elevation view thereof;

FIG. 13 is a top plan view thereof; and,

FIG. 14 is a bottom plan view thereof.

The broken lines depict portions of the camera that form no part of the claimed design.

1 Claim, 14 Drawing Sheets(56)
